UNITED STATES PATENT OFFICE.

EDWARD KANNAKA, OF STERLING, ILLINOIS.

DESIGN FOR A FOOT REST.

Application filed January 17, 1928. Serial No. 24,905. Term of patent 3½ years.

To all whom it may concern:

Be it known that I, EDWARD KANNAKA, a citizen of the United States, residing at Sterling, in the county of Whiteside and State of Illinois, have invented a new, original, and ornamental Design for a Foot Rest, of which the following is a specification, reference being had to the accompanying drawing, forming part thereof.

I claim:

The ornamental design for a foot rest, substantially as shown.

EDWARD KANNAKA.
